UNITED STATES PATENT OFFICE.

LEWIS S. BROWN, OF COLUMBUS, OHIO.

COIN-CONTROLLED TIRE-PUMP.

SPECIFICATION forming part of Letters Patent No. 605,696, dated June 14, 1898.

Application filed March 4, 1898. Serial No. 672,542. (No model.)

To all whom it may concern:

Be it known that I, LEWIS S. BROWN, of Columbus, in the county of Franklin and State of Ohio, have invented a new and Improved 5 Coin-Controlled Tire-Pump, of which the following is a full, clear, and exact description.

My invention relates to an improvement in pumps intended for use in filling the tires of bicycles and controlled by a coin, the pump 10 being released or put in operative position by the insertion of a coin and thrown into inoperative position by the removal of the wheel.

My invention consists of certain novel features of construction, which will be herein- 15 after described and claimed.

Reference is to be had to the accompanying drawings, forming a part of this specification, in which similar characters of reference indicate corresponding parts in all the views.

Figure 1 is a front elevation of my device, showing it in place applied to a bicycle. Fig. 2 is a side elevation of the lower portion of the device, showing the bicycle-wheel in place. Fig. 3 is a top plan view of the casing containing the wheel-support and the controlling apparatus. Fig. 4 is a side elevation, with one face removed, of that portion of the casing containing the controlling mechanism. Fig. 5 is a similar view of a portion of said 20 casing, showing the parts in a different position. Fig. 6 is a cross-section taken upon the line 6 6 of Fig. 4. Fig. 7 is a cross-section taken upon the line 7 7 of Fig. 4, and Fig. 8 is a cross-section taken upon the line 8 8 of Fig. 4.

The object of my invention is to provide a device within which a wheel may be inserted and connected with a hose for the purpose of pumping up the tire, the said device being 40 provided with a pump and the connection being made between the pump and the tire by inserting a coin in the device.

A frame A is mounted upon a suitable stand and is provided with two hooks B and B' of 45 such size and so placed as to receive the lower portion of a bicycle-wheel. To this frame is connected a vertical standard A', upon which is secured a third hook B², adapted to engage the upper portion of a bicycle-wheel, so as to 50 give the same a sure support.

Mounted upon the base alongside the frame A is a pump-cylinder P, consisting of a pis-

ton which is operated by means of a rod M³, which extends upward through suitable guides on the standard A', said standard consisting of two parallel members connected at their upper ends by an integral cross-bar, which bar is shown broken away in Fig. 1. To the rod M³ is pivoted a connecting-rod M², which at its other end is pivoted upon a crank-wheel M', mounted upon the same shaft as the wheel M, the latter being a fly-wheel provided with a crank or other suitable mechanism, by which it is to be revolved. The exact construction of the pump-operating mechanism is not essential. Any form of operating mechanism may be substituted for that described.

The upper portion of the frame A is provided with a casing C, provided with a chamber a, adapted to receive the mechanism by which the device is controlled, and with a receptacle C' to receive the coins. This casing has at one end a block R, which forms a valve-casing, and is provided at top and bottom with means, as nipples p², for the attachment of the two portions p and p' of a hose. The lower section p of the hose is attached to the pump, while the upper section p' is adapted to be connected with the tire. The block R has an aperture therethrough forming a seat for the controlling - valve. This valve is formed as a part of a rod D, which extends lengthwise of the casing C and is provided with a port d, adapted at will to form a connection between the pump and the tire or between the pump and the outer air. The block R, forming the valve-casing, is provided with three ports or passages, one port D' leading from the valve to the pump connection, another D² leading from the valve to the outer air, and the third D³ leading from the valve to the connection with the tire. The port d through the valve is adapted to connect the port leading to the pump with the one leading to the tire or to connect the port leading to the pump with the one leading to the outer air. This valve is of the same nature as the ordinary three-way valve.

Upon the rod D, which forms the valve, is secured a segment-arm E, to which is connected one end of a spring e, secured at its opposite end to the casing and acting to throw the arm E toward the coin-controlled lever G.

This lever G is pivoted at *g* to the side of the casing C and has one end entering the narrow channel G², formed in the body of the casing and covered by a plate II. The upper portion 5 of the channel G² is connected with the coin-receiving chute J, which is here shown as formed by securing a separate piece to the upper side of the casing. The chute is provided with an additional channel J', located 10 immediately beneath the aperture through which the coin is inserted. This passage J' is of such a width that the coin for which the device is intended will slide along the passage, while a smaller object will slip through it, and thus not act on the lever G. A coin 15 dropped in the chute will rest upon one end of the lever G and throw the opposite end upward, so as to remove it from the path of the segment-arm E. The rod D, carrying the 20 segment-arm E, is also provided with an arm or radial pin F, extending through a slot in the plate II in such a position as to limit the downward swing of the lever G and prevent the discharge of the coin I.

25 To enable the pump to be connected with the wheel, the valve must be turned so as to make a direct connection between the ports D' and D². In its normal position the valve is set so as to make a connection between the 30 ports D' and D². The segment-arm E, engaging the end of the lever G, will prevent the valve from being turned until a coin has been dropped into the chute. When the lever G has been thrown up by the coin, the 35 valve may then be rotated so as to make the connection between the ports D' and D². As the rod D is rotated the arm or radial pin F is swung downward, thus permitting the lever G to drop farther and to release the coin. 40 The periphery of the segment-arm E will engage the under edge of the lever G and prevent its dropping until the valve has been turned backward.

The hook B', which engages the bicycle- 45 wheel, has an arm or hook *b* pivoted thereon by the pin *b'*. When this hook *b* is swung toward the outer end of the hook B', it will pass over the inner side of the bicycle-rim and lock the same in place. Upon the outer end 50 of the rod D, which forms the valve, is fixed a lever K, and this lever is connected by a link *k* to the hook *b*, so that the two are operated together. The hook *b* and lever K are provided with apertures *b*², adapted to receive 55 the link *k* and by which the relative throw of the hook *b* and lever K may be adjusted. The upper end of the lever K is protected by a casing L, formed of plates secured to the end of the casing C.

60 The operation of my device is as follows: The normal position of the parts is that shown in Figs. 2, 3, and 4, in which the hook *b* is open, and the valve D connects the ports D' and D². With the parts in this position the 65 bicycle-wheel is placed within the supporting-hooks B, B', and B². A coin I is then inserted in the chute, which as it drops on the

end of the lever G throws the other end of the lever up, so that the valve may be turned into its operative position. This is accomplished 70 by engaging the lever K and turning the valve into the position shown in Fig. 7. After the upper section *p'* of the hose has been connected to the tire the pump may be operated to inflate the tire. When the tire has been 75 inflated, the lever K is thrown backward to the position shown in Fig. 2. This releases the wheel and at the same time permits the lever G to drop from the position shown in Fig. 5 to that shown in Fig. 4, in which the 80 valve-stem is locked, so that the pump cannot be used to furnish air for another tire until another coin is inserted in the chute J. By this means a coin must be inserted in the device for each tire inflated. 85

Having thus described my invention, I claim as new and desire to secure by Letters Patent—

1. A tire-pumping device, comprising a pump, a tube leading therefrom and adapted 90 to be connected with a tire, a valve interposed in said tube, a wheel-lock, connections between the wheel-lock and the valve, whereby the tire connections are broken when the wheel-lock is open, and a coin-released mechanism for controlling said parts, substantially as described.

2. A tire-pumping device, comprising a pump, a tube connecting the pump and tire, a valve interposed in said tube, a wheel-lock, 100 connections from the valve to the wheel-lock, a lever adapted to prevent opening of said valve, and a coin-chute adapted to deliver a coin upon said lever to swing it clear of the valve, to permit the opening of the valve, substantially as described. 105

3. A tire-pumping device, comprising a pump, a tube connecting the pump and tire, a valve interposed in said tube, a wheel-lock, 110 connections from the valve to the wheel-lock, a pivoted coin-operated lever, a segment-arm mounted upon the valve-stem and normally engaged by said coin-operated lever to prevent opening of the valve, and a coin-chute for delivering a coin to said coin-operated lever, substantially as described. 115

4. A tire-pumping device, comprising a pump, a tube connecting the pump and tire, a valve interposed in said tube, a wheel-lock, 120 connections from the valve to the wheel-lock, a pivoted coin-operated lever, a segment-arm mounted upon the valve-stem and normally engaged by said coin-operated lever to prevent opening of the valve, an arm upon the valve-stem, engaging the coin-operated lever 125 to prevent discharge of the coin until the valve is moved by hand, and a coin-chute for delivering a coin to said coin-operated lever, substantially as described.

5. A tire-pumping device, comprising a 130 wheel-support having a pivoted locking-hook adapted to secure the wheel in place, a pump, a tube connected to the pump and adapted for attachment to a tire, a valve interposed in

said tube, connections from the valve to the locking-hook, whereby the wheel is released when the valve is turned to cut off the air-supply, and a coin-operated mechanism controlling the valve, substantially as described.

6. A tire-pumping device, comprising a wheel-support having a pivoted locking-hook adapted to secure the wheel in place, a pump, a tube connected to the pump and adapted for attachment to a tire, a valve interposed in said tube, having an extended stem, connections from the valve to the locking-hook, whereby the wheel is released when the valve is turned to cut off the air-supply, a coin-operated lever, a coin-chute leading thereto, a segment-arm upon the valve-stem, normally engaging the side of the coin-operated lever, and an arm upon the valve-stem, normally extending under the coin-operated lever and stopping its swing short of the position where

the coin is discharged, substantially as described.

7. A tire-pumping device, comprising a wheel-support having a pivoted locking-hook adapted to secure the wheel in place, a pump, 25 a tube connected to the pump and adapted for attachment to a tire, a three-way valve interposed in said tube and adapted to connect the pump either with the tire connection or the open air, connections from the valve to 30 the locking-hook, whereby the wheel is released when the valve is turned to cut off the air-supply, and a coin-operated mechanism controlling the valve, substantially as described.
